UNITED STATES PATENT OFFICE

DAVID F. YOUNGBLOOD, OF SAN ANTONIO, TEXAS

DESIGN FOR A COMBINATION LAVATORY AND TOILET SEAT

Application filed October 9, 1929. Serial No. 32,985. Term of patent 14 years.

To all whom it may concern:

Be it known that I, DAVID F. YOUNGBLOOD, a citizen of the United States, residing at San Antonio, in the county of Bexar and State of Texas, have invented a new, original, and ornamental Design for a Combination Lavatory and Toilet Seat, of which the following is a specification, reference being had to the accompanying drawing, forming part thereof.

In the drawing:

The figure is a perspective view of a combination lavatory and toilet seat, showing my new design.

I claim:

The ornamental design for a combination lavatory and toilet seat, as shown.

In testimony, that I claim the foregoing as my own, I have hereunto affixed my signature.

DAVID FRANKLIN YOUNGBLOOD.
